Primary Examiner — Natasha Vujcic*Assistant Examiner* — Gilbert B Ford(74) *Attorney, Agent, or Firm* — Jose Cherson Weissbrot(57) **CLAIM**

The ornamental design for a leg cast protector, as shown and described.

DESCRIPTION

FIG. 1 is a top perspective view of a leg cast protector showing my new design;

FIG. 2 is a bottom perspective view thereof;

FIG. 3 is a front elevational view thereof;

FIG. 4 is a rear elevational view thereof;

FIG. 5 is a left side view thereof, the right side view being a mirror image of FIG. 5;

FIG. 6 is a top plan view thereof;

FIG. 7 is a bottom plan view thereof;

FIG. 8 is a partial enlarged view of FIG. 2; and,

FIG. 9 is an enlarged partial view of FIG. 7.

The dash dot-dot in the figures are for the purposes of illustrating portions of the leg cast protector, which form no part of the claim design.

The dash-dot-dash lines are for an notating enlarged views, which form no part of the claim design.

1 Claim, 9 Drawing Sheets
